UNITED STATES PATENT OFFICE!

THOMAS HISLOP RUSSELL, OF MARION, INDIANA.

INTERNAL-COMBUSTION ENGINE.

1,094,254.

Specification of Letters Patent. Patented Apr. 21, 1914.

Application filed March 26, 1912. Serial No. 686,305.

To all whom it may concern:

Be it known that I, THOMAS H. RUSSELL, a citizen of Great Britain, residing at Marion, in the county of Grant and State of Indiana, have invented new and useful Improvements in Internal-Combustion Engines, of which the following is a specification.

This invention has relation to the type of engines utilizing a gaseous mixture as the motive medium, the purpose being to simplify the construction of this type of engines and to materially reduce the number of working parts.

The invention provides a novel form of valve mechanism designed most especially for engines of the four cycle type and embodying multiple cylinders so that a single valve may control the admission of the gaseous mixture to more than one cylinder as well as regulate the outflow of the burnt gases therefrom.

The invention consists of the novel features, details of construction and combination of parts, which hereinafter will be more particularly set forth, illustrated in the accompanying drawings, and pointed out in the appended claim.

Referring to the drawings, forming a part of the specification, Figure 1 is a vertical longitudinal section of a multiple cylinder engine of the four cycle type embodying the invention. Fig. 2 is a horizontal section on the line 2-2 of Fig. 1. Fig. 3 is a transverse section on the line 3-3 of Fig. 1. Fig. 4 is an enlarged section of one of the valves and the bushing or lining. Fig. 5 is an enlarged horizontal section of the parts shown in Fig. 4.

Corresponding and like parts are referred to in the following description, and indicated in all the views of the drawings, by the same reference characters.

The engine illustrated is of the type embodying four cylinders which are cast in pairs or blocks. The cylinders of each pair or block are designated by the numerals 1 and 2 and have the usual surrounding space through which a cooling medium is circulated. A valve casing 3 is located intermediate the cylinders of each pair and is formed therewith as a part of the block. The valve casing 3 is of cylindrical form and is located at one end of the block and has a port 4 opening into each of the cylinders. A rotary valve 5 is arranged to op-

erate in each of the valve casings 3 and consists of a shell or hollow cylinder having a medial partition 6. Ports 7 and 8 are formed in the sides of the rotary valve 5 on opposite sides of the partition 6 and are adapted to alternately register with the ports 4 of the cylinders. Each valve casing 3 has an inlet port 9 at its upper end and an outlet or exhaust port 10 at its lower end. The gaseous mixture may be supplied to the inlet 9 in any manner well understood in the art and the burnt gases may pass off through the outlet 10 to a convenient point of discharge. The rotary valves 5 have a snug fit within their respective valve casings and are adapted to be rotated in any manner from the crank shaft of the engine. It is to be understood that each of the valves 5 makes one complete revolution for each two complete revolutions of the crank shaft and the power transmitting means must be such as to maintain this relative movement. A recess 11 is formed in the outer side of each of the valves 5 and is of a size corresponding with the port 4 and registers therewith during combustion and expansion of the gases. The recess 11 prevents carbon depositing upon the working surface of the valve.

It is not practically possible to cast the ports 4 in the cylinders with such accuracy as to obtain the best possible results in the operation of the engine, hence the upper portion of each valve casing is bored to receive a cylindrical bushing or lining 12 which has ports formed therein to register with the ports of the cylinders. The ports of the bushings or linings 12 may be finished either by hand or machine so as to obtain the best possible results, after which the bushings or linings are pressed home into their respective valve casings. Longitudinal grooves 13 are formed in the inner walls of the bushings or linings and receive packing strips 14 of asbestos or other material so as to insure a close joint between the valve and its casing. The ends of the bushing are likewise grooved or rabbeted to receive packing gaskets 15 for a like purpose, namely to obtain a tight joint between the ends of the bushing and the adjacent parts.

Each of the valves has a rod or stem 16 to which is secured a worm gear 17, which is arranged to mesh with a worm 18 provided upon the crank shaft 19. It is to be understood that the mechanism illustrated

for transmitting motion from the crank shaft to the rotary valves is one of many forms that may be employed to effect a like result and has been selected for simplicity of illustration. The provision of a single valve for a number of cylinders simplifies the construction and operation and reduces the number of working parts, with the result that repairs and adjustments are adapted to be economically and easily made. The valves being of the rotary type avoid the use of springs and the trip mechanism incident to the variety of explosive engine employing puppet valves. It is also observed that the operation of the engine is rendered noiseless so far as the valve mechanism is involved, since there is no sound such as produced by the action of puppet valves and the trip mechanism therefor including valve lifters and the operating cams. It is to be further understood that in the arrangement of the parts the pistons are so set as to operate in successive order.

From the foregoing description, taken in connection with the accompanying drawings, the advantages of the construction and of the method of operation will be readily apparent to those skilled in the art to which the invention appertains, and while I have described the principle of operation of the invention, together with the device which I now consider to be the best embodiment thereof, I desire to have it understood

that the device shown is merely illustrative, and that such changes may be made when desired as are within the scope of the claim appended hereto.

Having thus described the invention what is claimed as new, is:—

In an internal combustion engine, the combination of a cylinder having a port, a cylindrical valve casing in communication intermediate of its ends with the port of the cylinder and provided at opposite ends with ports for the inlet of the gaseous mixture and an outlet for the burnt gases, a cylindrical bushing fitted snugly within the valve casing and having a port in line with the port of the cylinder and provided at its ends and sides with packing, and a rotary valve arranged within the bushing, said valve being hollow and having its ends in communication with the ports in the respective ends of the valve casing and provided with a medial partition and having ports in its sides upon opposite sides of said medial partition and at different points in its circumference to alternately register with the port of the bushing leading into the port of the cylinder.

In testimony whereof I affix my signature in presence of two witnesses.

THOMAS HISLOP RUSSELL.
